US00D730342S

(12) United States Design Patent
Kim et al.

(10) Patent No.: US D730,342 S
(45) Date of Patent:  May 26, 2015

(54) COVER FOR MOBILE PHONE

(71) Applicant: Samsung Electronics Co., Ltd.,
Suwon-si (KR)

(72) Inventors: Yoon-young Kim, Seongnam-si (KR);
Min-a Oh, Gwangju-si (KR)

(73) Assignee: Samsung Electronics Co., Ltd.,
Suwon-si (KR)

() Term: 14 Years

(21) Appl. No.: 29/476,426

(22) Filed: Dec. 13, 2013

(30) Foreign Application Priority Data

Sep. 30, 2013 (KR) 30-2013-0049603

(51) LOC (10) Cl. 14-03

(57) CLAIM

The ornamental design for a cover for mobile phone, as shown and described.

DESCRIPTION

FIG. 1 is a front perspective view of a cover for mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the cover for mobile phone are for environmental purposes only and form no part of the claimed design.

1 Claim, 7 Drawing Sheets
